UNITED STATES PATENT OFFICE.

CHARLES F. KARBERG, OF CLEVELAND, OHIO, ASSIGNOR TO THE CLEVELAND-AKRON BAG COMPANY, OF CLEVELAND, OHIO, A CORPORATION.

AWNING-OPERATING MECHANISM.

1,190,909.

Specification of Letters Patent.

Patented July 11, 1916.

Application filed February 8, 1915. Serial No. 6,942.

To all whom it may concern:

Be it known that I, CHARLES F. KARBERG, a citizen of the United States, residing at Cleveland, in the county of Cuyahoga and 5 State of Ohio, have invented certain new and useful Improvements in Awning-Operating Mechanism, of which the following is a specification.

This invention pertains to an improvement 10 in awning operating mechanism as compared, especially, with Letters Patent of the United States issued to I. J. Daniels, and bearing Nos. 546,730, of Sept. 24, 1895, and 784,475, of May 7, 1905, respectively 15 and owned by The Cleveland-Akron Bag Company, the assignees of this invention.

The improvement consists in the material 20 differences in the construction and combination of parts as shown and described and particularly pointed out in the claims.

In the accompanying drawings, Figure 1 is a rear elevation of the casing and parts 25 therein as seen from the left in Fig. 2, and Fig. 2 is a vertical sectional elevation front to rear of the complete device in working condition. Sheet 2 of the drawings contains 30 sundry details of the parts. Thus, Fig. 3 is a perspective view of the shaft coupling. Fig. 4 is a perspective view of the pivotally 35 mounted detent or dog which locks the parts against unwinding. Fig. 5 is a perspective view of the rod that supports said detent. Figs. 6 and 7 are perspective views of the 40 two operating gears, and Figs. 8 and 9 are perspectives of the two sections of the casing.

As thus shown, the first essential improvement over the two patents above referred to is found in the inclosing casing. In the said patents the casing or housing 45 for the operating parts consists in a box cast in a single piece within which the operating parts are mounted and the only opening or entrance to the parts for approach or removal is at the rear, which is closed by bolting the box to its support. Hence, the 50 gears and all the other contained parts are effectually locked in and cannot be reached without bodily detaching the box with all its heavy contents. Experience has demonstrated that this is an inefficient device and 55 inconvenient in use as well as being otherwise objectionable, as when a spring or other part becomes displaced or unserviceable and has to be fixed or replaced. The said casing is also otherwise improved by the present

change as will presently appear. Thus, the casing is constructed in two parts or sections *c* and *c'*, front and rear, respectively. The rear or inner section which is also the main section, is provided with a diaphragm or 60 wall *w* across its front which extends about half way up and is featured with two journal bearings *b* and *b'* at right angles to each other and an opening *b*² about its middle to support a rod. Above said wall the front 65 of the said section is open to provide a working space for the horizontally disposed bevel or miter gear *g'*, the actuating gear in mesh therewith being positioned at the front of said wall within the section *c* of 70 the casing. Practically, the two gears and all the other working parts are mounted in or upon the said wall plus the two bearings in the casing itself. Thus, the initial or actuating gear *g* has a tapered tubular 75 spindle 2 which occupies the correspondingly shaped bearing *b* in said wall and at its front in the section *c*, while the gear *g'* is supported over or upon said diaphragm by the shaft coupling member *m*, which has an 80 angular shank 3 on which the said gear is engaged and a cylindrical extremity 4 beneath said gear adapted to rotate in the bearing *b'*. A divided bearing *b*³ having one half in the top of each of the two casing 85 sections, is formed in line with the bearing *b'* and serves as a further support for the coupling member *m* and releases said member for removal when the front section *c'* is detached. The said member is provided 90 with a yoke 5 at its top adapted to attach an operating shaft thereto, and said member is driven by and through the gear *g'*.

The gear *g* is removably mounted on the square shank 6 of the shaft *n*, which shank 95 is of such length in the said gear that the shaft can be moved back and forth axially within all operating requirements and still hold its working relations with the said gear. The inner portion of said shaft is 100 formed with a stem which is slidable in the tubular extension 2 of the gear *g* within limits, or as much as may be required to operate the detent or dog *d*. The operating or crank handle *h* is mounted in a sleeve 105 or head *h'* on the outer end of the said shaft and serves to both rotate the shaft and the gear thereon and to slide the shaft back and forth according to the position desired at a given time for the control of the detent *d*. 110

The said detent is hung in its own side bearings 8 on a transverse rod 9 fixed at its ends in the rear middle portion of the main casing section *c*, and is further provided with 5 a tooth 10 on its inside and top and an arm 12 at its bottom provided with a hole near its end in registering relations with the spring supporting rod 14, supported at its inner end in the hole *b*² in the said diaphragm and in which the said rod is fixed fluid tight. A spiral spring 15 is mounted on said rod between said arm and the said wall and serves to normally press outward on the arm 12 and keep the dog or detent 10 *d* in locking engagement with the gear *g*'. To this end the said gear has a hub provided with a series of pockets or recesses 16 at intervals about its top, four in this instance, and adapted to be engaged by the tooth 10 15 when the said dog is in normal position. That is, when the awning is wound up and the shaft *n* withdrawn a suitable distance to release said dog, it will be instantly forced into engaging position by the spring 15 and 20 will remain there until purposely released by thrusting said shaft inward, say to the extent shown in Fig. 2, and throwing the dog or detent back out of engagement. It will be seen in Fig. 4, especially, that said 25 dog has a hump or lug 18 at the base of arm 12 relatively between the pivot bearings 8 and provided with a beveled or more or less rounded under surface adapted to be engaged by the said shaft *n* and whereby the 30 dog is forcibly swung back at its top and inward at its bottom when the stem *s* is thrust inward until the gear *g*' is released. At this time the operator has hold of the 35 mechanism so that he can raise or lower the awning at pleasure.

It is to be especially noticed by the foregoing construction, that the dog is held back out of locking position as long as the shaft 40 *n* is projected inward, as seen in Fig. 2, an opening in the dog affording room for the said shaft at the base of said hump, and the detent is thus locked against the tension of 45 its spring and cannot swing back to engaging position until the said stem is purposely withdrawn. This remedies the serious former defect of having the dog constantly free to swing to locking position under 50 heavy spring pressure as formerly and compelling the operator to exert a constant inward pressure to overcome the tension of the spring. In the present construction, the shaft *n* locks the dog back out of engagement until it is purposely released, and the 55 spring operates simply against the dog and never against the shaft. This contributes 60

very materially to the easy operation of the awning as compared with the former construction.

The handle or crank *h* is detachably secured to the end of shaft *n* by a set screw 19 through the integral loop *h*' on the end of the shaft. Of course, the said shaft can be bodily withdrawn at any time and removed with the handle, and the front casing 70 section can then be detached without disturbing any of the operating parts but which also will be exposed for removal, one or all, as may be needed. In fact, all the parts can be separately removed from the front of the 75 casing, when duly released and the opening over the diaphragm or wall *w* affords access to the dog *d* and the spring at the rear. The said wall also provides a lubricating pocket or chamber in the front of the casing 80 in which the gear *g* is slightly immersed and which carries the lubricant to other parts.

What I claim is:

1. A casing as described consisting of front and rear sections, the rear section having a vertically disposed integral wall substantially half its depth at its inside and provided with journal bearings at right angles to each other, a transmitting gear having a journal mounted in one of said bearings and an actuating gear having a tubular spindle mounted in the other bearing, in combination with a pivoted detent having a projection on its inside and provided with a hump adapted to engage said transmitting 90 gear, and a shaft projected through said actuating gear and the spindle thereof and adapted to contact with said projection and release said detent.

2. A device of the class described, comprising an inclosing casing and a transmitting gear and an actuating gear in mesh at right angles with each other in said casing, in combination with a detent of substantially T shape, a rod extending transversely 105 through said casing and having the detent pivoted thereon said detent being provided with a tooth adapted to engage the transmitting gear and with a projection near its middle and front, and a shaft in rotating 110 relation with said actuating gear and having a stem projected through the axis thereof into contact with said projection on said detent and adapted to throw and hold the detent back out of engagement with said 115 transmitting gear.

In testimony whereof I affix my signature in presence of two witnesses.

CHARLES F. KARBERG.
